TRUSS

Walter H. Barlow, Stroud, Okla.

Application April 20, 1939, Serial No. 269,006

1 Claim. (Cl. 128—117)

This invention relates to trusses for treatment and reduction of rupture known as hernia.

An object of the invention is to provide a truss having a pressure spring adapted to embrace the wearer's body, and a pad carried by the spring adapted to yieldably bear against the rupture and swing with the body motion of the wearer to exert a counter pressure at the particular angle which the wearer's body exerts pressure against the pad, for the purpose of holding the rupture in place and massaging the body tissues.

A further object is to provide a truss having a pad formed of two sponge rubber chamois skin covered sections assembled as a unit and coacting to simulate pressure of the fingers and arm of a person pushing a rupture back in place.

A further object is to provide a truss adapted to automatically govern the pressure applied, so that unusual strain upon the affected part, causing a bulge, will occasion additional pad pressure upon that particular part and thus meet or equalize conditions which arise by the flexing of muscular tissue, without irritation to the surface of the skin or without discomfort to the wearer.

A further object is to provide a truss which will be formed of a few strong, simple and durable parts which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a perspective view of a truss constructed in accordance with the invention.

Figure 2 is a longitudinal sectional view of the pad.

Figure 3 is a cross sectional view of the pad taken on the line 3—3 of Figure 2.

Figure 4 is a longitudinal sectional view of one of the sponge rubber sections which is concave on the top and bottom faces as initially formed.

Referring now to the drawing in which like characters of reference designate similar parts in the various views, the outer section of the pad is shown to comprise a blank 10 of sponge rubber formed with a flat bottom surface 11 and a slightly arched top surface 12 merging with the bottom surface at the edge of the blank in curve

surfaces 13. The blank is substantially oval in contour. The purpose of thus shaping the blank is to simulate the ball or tip of a person's finger.

The blank 10 is backed through the medium 5 of a leather or other backing 14 disposed against the flat bottom surface 11 of the blank and extending throughout the entire area of the surface. Preferably four small bolts 15 are passed through the backing as best shown in Figure 3. A chamois skin facing 16 is drawn smoothly over the sponge rubber blank 10 and directed along the lower face of the backing 14. The edges are drawn toward each other through the medium of stitching with thread as shown at 10 15 17 to secure the facing in place.

The base section of the pad comprises a blank 18 of sponge rubber, of greater thickness than the blank 10, and the top and bottom faces are concave as shown at 19 to provide greater thickness 20 at the periphery than at the center. As best shown in Figure 2 the blank 18 is provided with stiff backings 20 and 21, preferably formed of leather, disposed respectively upon the upper and lower faces of the blank. A substantially 25 oval ring 22 of comparatively stiff material is interposed between the upper backing 20 and the sponge rubber blank 18 to form a wearplate for the nuts 23 of the bolts 15.

A chamois skin facing 24 is smoothly stretched over the backing plate 20, sponge rubber blank 18 and backing plate 21. The edges of the facing are drawn tightly toward each other on the bottom face of the backing 21 through the medium of thread 25 stitched through the edge portion of the facing. When the facing is thus applied the initial shape of the section 18, as shown in Figure 4, is changed so that the blank 18 fills in all of the space between the backings 20 and 21 but the sponge rubber is under greater tension at the edge portion than at the center to simulate movement of the arm of a person applying pressure at various angular directions to push a rupture back in place.

A plate 26 of any suitable stiff material is cemented or otherwise secured to the facing 24 on the bottom face of the backing 21. A pair of bolts 27 is secured to the plate 26 along its center median diameter as best shown in Figure 1.

The pad is secured to a pressure spring 28 formed of steel wire bent in the form of a loop to embrace a portion of the body of the wearer. The spring is provided with a substantially triangular shaped plate 29 at one end having an opening 30 to receive one of the bolts 27, which 50 later forms a pivot bolt, and is also provided

with an arcuate slot 31 concentric with the opening 30 to receive the other bolt 27 which later forms an adjusting bolt to adjust the position of the pad relatively to the spring. The spring is provided at the opposite end with a conventional pad 32 for contact with the body of the wearer.

A fastening strap 33 for the truss is provided at one end with an elastic strip 34 which is attached to the conventional pad 32 in any preferred manner. The free end of the strap is provided with a series of openings 35 adapted to interchangeably receive a screw 36 which is threadedly engaged in the plate 26 as shown in Figure 1. The strap is merely for the purpose of assisting in holding the pad in place rather than for causing the pad to exert additional pressure. All of the pressure exerted is exerted by the spring 28 itself.

The spring is rigid but can be adjusted up or down to any position on the body required to meet the particular condition presenting itself in any class of rupture and the pad can be adjusted on the spring in any way necessary to meet that condition.

The chamois skin covering is washable and also clings to the skin and will not irritate the skin due to its porousness. The surface of the chamois skin covering the contact section of the pad, which comes in contact with the skin, adheres to the particular point where it is set, and the pad section behind the contact section performs the pressure movement to meet the distended part.

In operation, the pad will massage the affected part at every move of the body, and due to the flexibility of the soft spongy rubber centers of the pad sections, the outer pad section which contacts the skin surface of the wearer will remain intact at all times, but the movement of the wearer's body causes a flexing motion against the contact section, through the base section of the pad, and this occasions the massage of the affected parts.

From the above description it is thought that the construction and operation of the invention will be fully understood without further explanation.

What is claimed is:

A truss comprising a pressure spring adapted to embrace a portion of the body of the wearer, a pair of sponge rubber blanks of substantially equal diameter superposed upon each other to form a pad, chamois skin facings smoothly stretched over the blanks, stiff backings for the blanks, means connecting the backings together, one of the blanks having a flat bottom surface and a slightly arched top surface merging with the bottom surface at the edge of the blank in a curve to simulate the concave on the top and bottom faces of the ball or tip of a person's finger, the other blank being shaped to provide greater tension at the edge portion than at the center to simulate movement of the arm of a person applying pressure at various angular directions to push a rupture back in place, and means attaching the pad to one end of the spring.

WALTER H. BARLOW.
